UNITED STATES PATENT OFFICE.

CHARLES MESSICK, OF HACKENSACK, NEW JERSEY, ASSIGNOR, BY DIRECT AND MESNE ASSIGNMENTS, TO ELECTRICAL CONVEYING MACHINERY COMPANY, A CORPORATION OF NEW YORK.

METHOD AND MACHINE FOR MAKING TREADS.

1,299,987.

Specification of Letters Patent.

Patented Apr. 8, 1919.

Application filed April 6, 1911. Serial No. 619,258.

To all whom it may concern:

Be it known that I, CHARLES MESSICK, a citizen of the United States, residing in Hackensack, county of Bergen, and State of 5 New Jersey, have invented a new and useful Improvement in Methods and Machines for Making Treads, of which the following is a specification.

The object of my invention is the production of "safety treads" so called, for stairs, platforms, and the like. These safety treads consist of a base-plate and a surfacing, the former being usually of sheet steel (to give mechanical strength and to afford 10

attachment to the stair or other installation), and the surfacing being usually of carborundum or other granular abrasive material embedded in a binder of lead or other soft metal.

20 The manufacture of such treads, particularly in a wholesale, commercial manner, has hitherto been unsatisfactory, though different schemes have been attempted, without as yet marked success. Among other 25

objections, it has been found that when it is sought to combine the carborundum with molten lead, the former will rise to the surface without being properly fixed throughout the binder; again, difficulty has been 30

found in properly securing the carborundum-lead surfacing to the base-plate, for example because the mechanical means (such as undercut grooves and the like) which have been previously attempted, present a slippery metal surface to the foot of 35 the pedestrian, thus impairing the efficiency of the anti-slip feature.

In carrying out my present invention, I first provide a two-part mold, within which 40 I place a suitable base-plate (preferably of tinned sheet steel or the like) and then fill the mold with carborundum or other suitable abrasive material, and secure the parts of the mold together temporarily, as by 45 spring-clips, to constitute a "casting-unit"; then such units are passed, successively, through a tank containing molten lead (or other suitable binder), whereby the carborundum and lead are simultaneously and 50 permanently bound together and bound to the tinned base-plate. Each casting-unit in turn serves to propel the units in front of it, and is itself propelled by the succeeding units of the series.

More specifically, in carrying out this 55 process, I employ a preferred form of apparatus that comprises four main features, to wit: (1) means for receiving each casting-unit and removing the temporary clamps, while holding the parts of the unit together 60 and delivering the same to the feeding-mechanism; (2) means for feeding forward each casting unit in turn, and thereby feeding the units in front of it through the molten lead; (3) the casting-means, containing 65 the molten binder (lead); and (4) means for cooling and delivering the molds and their contents.

The invention consists of the new method of manufacturing anti-slip treads or similar 70 articles; and also of the new apparatus for carrying out the process, and particularly of the molten-lead tank provided with a continuous passageway for the molds, without permitting loss of the molten material. 75 The invention further comprises the new forms of the features above indicated, as well as the various combinations thereof. The invention further comprises the various details of construction and arrangement as 80 hereinafter set forth and claimed.

My invention will be best understood in connection with the following description of a preferred embodiment of the apparatus for carrying it out, as illustrated in the 85 annexed drawings. But the invention is not limited to the precise construction and arrangement of parts, or to the specific details of operation therein set forth; and especially my new process may be carried out 90 by other and different mechanical means than those shown.

In the annexed drawings, Figure 1 is a side view of the complete 95 machine;

Fig. 2 is a longitudinal section through the machine, the central portion being broken away;

Fig. 3 is a top view of the same, the central portion being broken away as in Fig. 2; 100

Fig. 4 is a transverse section through the line 4-4 of Fig. 3, viewed from the right;

Fig. 5 is a similar view through the line 5-5 of Fig. 3;

Fig. 6 is a transverse section, on a larger scale, through the line 6-6 of Fig. 1, viewed from the right; 105

Figs. 7-11 illustrate, on a larger scale, the

mold, the "casting-unit", and the finished tread, wherein

Fig. 7 is a plan of the casting-unit, with its cover partly broken away to show the 5 contents;

Fig. 8 is a side view of the same;

Fig. 9 is a transverse section through the mold and the base-plate therein;

Fig. 10 is a perspective of a completed 10 anti-slip tread; and

Fig. 11 is a section of a modified form of tread, with an extra thick nosing.

Referring first to Figs. 7-9, the reference-numeral 21 indicates a mold, shown 15 as a long, narrow, shallow pan, open at both ends, and having a longitudinally-corrugated floor. Upon the floor is laid a tinned iron base-plate 23, which eventually is to become a portion of the tread, as will 20 be more fully described. The mold is closed by the cover or cope-plate 22, which is bent down at one end as shown at the right of Fig. 8, to close one end of pockets formed on the face of the base-plate by the corrugations of the mold 21. The mold and the 25 cope, containing the base-plate, are clamped together by the temporary clamps 24. Carborundum or other granular abrasive is poured into the open mouth of the pockets, 30 and after they are completely filled a little shellac may be applied to the mouths to prevent the carborundum from jarring out in handling. Although the cope is apparently fitted closely upon the mold, nevertheless, 35 there is sufficient space at the hair-line junction to permit the molten lead to enter, reach the carborundum, and fill all the voids within the mold.

A mold thus filled and clamped constitutes a "casting-unit". Preferably a number of these units will be prepared beforehand, in readiness for the casting operations. In casting, one of these units is introduced, by hand, into the front of the apparatus, which first strips off the temporary clips 24 and substitutes its own clamping-action, and then feeds the unit forward; then, another unit is similarly introduced and stripped and fed forward, serving to 40 propel its predecessor; and so on continuously,—the casting-units being thus fed continuously through the molten lead and through the cooling-zone, until they and their finished castings are successively discharged at the rear of the machine, where the castings can be removed from their respective molds.

The apparatus as a whole is seen in Fig. 1. At the center is the casting-mechanism 60 which comprises an open-ended trough 10, having a longitudinally inclined floor, and being supported upon legs 14-15 and steadied by braces 16. At the right is shown the extension-plate or slide-bar 18, steadied 65 by braces 17, which carries the stripping and

the feeding mechanisms; and at the left are the cooling-means 67. The casting-units, as 25, are introduced at the upper end (at the right of Fig. 1), and discharged at the left. Fig. 2 shows also one of the intermediate casting-units 26, and still another unit 27 about to emerge from the cooling-region at the end of the machine.

The receiving and stripping mechanism comprises the stationary wedge-shaped 75 stripper 28, projecting from a block 29 that is secured upon the outer end of the T-shaped slide 18, and a similarly-shaped upper stripping-plate 30, yieldingly secured above the lower stripper, as by means of the 80 depending rods and springs 31-32. The upper face of the stationary stripper 28 is centrally and longitudinally channeled out to receive the casting-unit, this guide-channel being preferably made somewhat flaring at its entrance (as indicated by dotted lines at the right of Fig. 3). As each unit 85 (25) is introduced, the sloping noses of the strippers 28 and 30 strip off the spring-clamps 24, but not until the tension of the 90 springs 32 has already been substituted to clamp the two parts of the mold together.

In front of the strippers, and also upon the slide-plate 18, is slidingly-mounted the lower gripping-jaw 33 which carries with it 95 the upper gripping-jaw 34. The lower jaw 33 has downwardly-depend ing arms which straddle the slide-plate 18, and is centrally and longitudinally channeled in its upper 100 surface to receive the casting-units and also to receive the horizontal member of the upper gripping-jaw 34, which latter is an inverted T in cross-section, having a longitudinal and centrally-located upwardly-extended flange. Horizontal guide-pins 52-53 105 extend from each side of the upper jaw 34, and lie in vertical slots in the marginal flanges of jaw 33,—whereby the two jaws are locked together longitudinally but can have relative movement in vertical direction. In the depending arms of the lower jaw is mounted the transverse shaft 47; the floating counter-shaft 48 is located in a slot in the top of the upper jaw; and two floating pivots 45 and 46 (lying in the prolongation of the same line) are connected to the shafts 47 and 48 respectively by the pairs of parallel links shown in Fig. 5. This construction, as seen in Fig. 1, constitutes a toggle so arranged that when the 110 pivots 45 and 46 are forced forward (to the left in Fig. 1), the two jaws 33 and 34 are forced together; whereas movement of the pivots in the opposite direction tends to separate the two jaws. A set-screw 49, 115 turning through the counter-shaft 48 and provided with a jam-nut, abuts against the upper jaw 34 and provides vertical adjustment of the parts. Two rearwardly extending springs 50 and 51 are secured to 120

125 130

the depending arms of the lower jaw 33, and are connected to the lever 54 that is pivoted near the rear end of the slide-bar 18. By moving the lever 54 from the depending position indicated in Fig. 2 into the position indicated in Fig. 1, the gripping-jaws are drawn rearward bodily. A set-screw having a handwheel 55, turns in a lug 56 (Fig. 4) depending from the block 29, and is alined with an abutment 57 (Fig. 3) carried by the lower jaw 33, for adjustably limiting the rearward travel of the gripping-jaws.

Rising from the block 29 are two arms 38 and 39, in which turns the transverse shaft 36, driven by power, as through the belt-wheel 37 (Fig. 3). On this shaft are mounted the eccentrics 41 and 42 carrying the pitmen 43 and 44, which latter are shown as having lost-motion engagement with the floating-pivots 45 and 46. Preferably, the parts are so adjusted that when the lever 54 is in the depending position indicated in Fig. 2, the rotation of the power-shaft 36 causes the pitmen to reciprocate idly upon the floating-pivots; but when the lever 54 is raised into the position shown in Fig. 1, this brings the pivots 45 and 46 within reach of the two abutments of the pitmen. This furnishes an intermittent feed: During the forward travel of the pitmen the gripping-jaws are first brought together (to seize the interposed casting-unit) and then moved forward bodily; and during the rearward movement of the pitmen, the gripping-jaws are first forced apart (releasing the casting-unit) and then drawn rearwardly.

To prevent any rearward travel of the casting-unit, a sort of sliding pawl is provided, comprising the eccentric quadrant 35 journaled loosely upon the power-shaft 36 and carrying a pivoted dog 40, the upper stripper-plate 30 being cut-away to permit the nose of the dog and the quadrant to enter the channel. As shown in Fig. 2, the maximum eccentricity of the quadrant 35 is in the horizontal direction and its minimum eccentricity in the vertical direction. When the first casting-unit 25 is inserted, its forward end abuts against the dog 40 and forces the latter forward, lifting the quadrant, until the farther travel of the unit releases the dog, whereupon the quadrant 35 drops back and grips the casting-unit 25, holding it against any tendency to rearward movement.

The casting-mechanism comprises the open-ended main trough 10, having the longitudinally-inclined floor 11 and the side-walls 12 and 13, within which is the floating or "lead-pot" 58, whose bottom is parallel to floor 11 and has an opening (near the forward and lower end thereof, see Figs. 1, 2, and 6) that affords an outlet into the main trough. Preferably the rear end-walls of

the floating-trough have hooks or shoulders 62 (Fig. 2), engaged by the transverse-bar 63, so that the parts may be yieldingly adjustable, as by means of the spring and hand-wheel 64; and the lower and forward end of the floating trough may be similarly held under yielding and adjustable pressure, as by a similar transverse-bar and spring controlled by the handwheel 65. The space between the floor of the main trough and the apertured bottom of the floating lead-pot 58, constitutes the casting-chamber or channel—the tension of the spring-devices at 64 and 65 clamping the casting-unit. Preferably, when the device is not in operation a blank or "dummy" of iron, of the same dimensions as a casting-unit, is interposed between the floor of the main trough 10 and the bottom of the float-trough 58. Beneath the troughs 10 and 58 is a plurality of gas-burners from the pipe 59.

Beneath the continuation of the floor 11 of the main trough 10, is a water-compartment 60; and at the rear of the floating-trough 58 is carried another water-compartment 67. 66 is a filling of asbestos, interposed between the melting-trough 58 and the water-compartment 67. Cold water is introduced into compartment 60, through pipe 68; thence it passes, through pipe 69, into the compartment 67, whence it escapes through pipe 70. 61 is a table or continuation of the floor of the trough, upon which the cooled casting-units are discharged. The cooling-compartment 67, in addition to cooling the casting-units, cools the adjacent portions of the side-walls of the troughs; and thus any molten lead that may tend to leak out in the clearance between the troughs 10 and 58, is frozen and forms a lead-packing to prevent the leaking out of the lead.

At the outset, one of the dummy-plates having been placed beneath the floating lead-pot 58 (or left there from a previous operation), sufficient lead or other binder having been supplied in the floating-trough 58, the burners 59 having been lighted, and the troughs and contents having been heated up more than sufficiently to melt the latter, the operator starts the revolution of the shaft 36, and then inserts a casting-unit 25 into the channel between the strippers and starts it forward; the spring-clamps are removed by the wedges, and the clamp-action of springs 31—32 is substituted, while the unit is being pushed forward and the quadrant-pawl 35 is caused to engage upon the top of the unit; then the operator inserts a second casting-unit, which is acted upon as before, and meantime the first unit (having entered the space between the then-separated gripping-jaws 33—34) is gripped by the jaws and carried forward, the quadrant 35 preventing any tendency to rear-

ward movement; and so on continuously, the first casting-unit shoving the dummy out of its way and entering the casting-channel, where it is subjected to the casting operation, and thence being forced by the succeeding units into the cooling-zone between water-compartments 60 and 67, where it is properly cooled and the casting solidified; and finally the unit is discharged along the extension-table 61, where the same operator, or an assistant, will remove the cope from the mold and take out the casting and put it to one side.

I have thus described my invention with great particularity of detail, but only for the sake of clearness, and as applied to manufacturing anti-slip treads, since the invention could be applied to the manufacture of other articles, and parts may be omitted and other parts substituted, and modifications may be made in the construction and arrangement of the parts, without departing from the spirit of my invention. For instance, some other stripping-mechanism might be made use of, or the stripping-device might be omitted altogether and the cope held upon the mold by hand until inserted into the machine. Again, some other form of feeding-device might be substituted in place of the gripping-jaws 33—34; and, indeed, the mold and cope with their contents might be held together by hand, and inserted directly into the casting-channel. So, also, it is obvious that various other forms of cooling-devices could be employed; or, if desired, the mold and its contents, while still hot, could be discharged from the casting-mechanism, and allowed to cool in the open air. But the best results are obtained by the combination of the inter-related mechanisms which coöperate in simultaneously or successively stripping, holding, guiding, feeding, casting, and cooling the casting-units, to provide the continuous manufacture of the completed product.

Having thus described my invention, I claim:

1. In a tread-manufacturing apparatus, the combination of spring-clamped jaws with wedge-shaped noses for receiving casting-units or two-part molds and removing therefrom temporary clips, feeding-mechanism for receiving said units from said jaws and propelling the same in a continuous series, and a casting-chamber and a cooling-chamber forming a continuous passageway in front of said feeding-mechanism.

2. In a tread-manufacturing apparatus, the combination of an open-ended trough having an inclined bottom, a second trough located therein and having an opening that communicates with the first-named trough, means such as a blank dummy or a casting-unit for spacing the inner trough above the floor of the outer trough to constitute a cast-

ing-chamber, means for clamping said troughs upon said spacing-means, said spacing-means serving to close the outlet of said chamber, and means for heating said trough.

3. In a tread-manufacturing apparatus, the combination of an open-ended trough, a second trough located therein and having an opening that communicates with the outer trough, means such as a blank dummy or a casting-unit for spacing the inner trough above the floor of the outer trough to constitute a casting-chamber and to close the outlet therefrom, and means for clamping said troughs upon said spacing-means.

4. In a tread-manufacturing apparatus, the combination of an open-ended trough, a second trough located therein and having an opening that communicates with the first-named trough, and means such as a blank dummy or a casting-unit for spacing the inner trough above the floor of the outer trough to constitute a casting-chamber and to close the outlet therefrom.

5. In a tread-manufacturing apparatus, the combination of a casting-trough for molten lead or the like and a cooling-region in front thereof, with a continuous passage-way through the two, and means for automatically feeding a series of molds or casting-units continuously through said passageway.

6. The combination with a tread-manufacturing apparatus which comprises a casting-chamber with a continuous passage therethrough, of a casting-unit adapted to pass through said passage and to close the outlet therefrom, consisting of a two-part mold having detachable clips securing together the parts of said mold.

7. In a machine for making treads, a casting-machine comprising a lead-pot having a troughlike bottom adapted to act as a slide through which a mold may be slid, and a movable cover for the slide, cooling-devices at the lower end of the slide, and a propelling-mechanism to propel a mold and contents through the slide.

8. In a machine for making treads, a casting-machine comprising a lead-pot having a troughlike bottom adapted to act as a slide through which a mold may be slid, one member of the slide being movable to adapt it to compensate for unevenness of the mold and for expansion or contraction, and cooling-devices at the lower end of the slide.

9. In a casting-machine to cast articles of soft metal, a machine comprising a lead-pot, a mechanism to propel a mold bodily through same, and molds capable of being propelled bodily through the lead-pot, whereby a series of heated-mold-castings may be made in the molds during their passage through the lead-pot.

10. In a casting-apparatus, the combination of a lead-pot having a passageway therethrough, a mold adapted to travel bodily

through said passageway, and means for propelling said mold bodily through said passageway.

11. In a casting-apparatus, the combination of a casting-trough, for molten lead, a movable member mounted yieldingly therein to exert pressure downward, and a cooling-device adjacent one end of the latter to freeze the lead located in the adjacent portion of the space between the side-walls of said trough and said movable member.

12. The herein-described process of making treads, which consists in providing the face of a foundation plate with fusible material, holding a mass of abrasive particles in definite form against the face of said plate, and uniting said particles into a homogeneous mass and simultaneously connecting said mass to said plate by filling the interstices 20 with the molten metal.

13. The process of binding granular particles in place upon the surface of a metal plate, which consists of introducing a soft metal into the interstices between the granular particles themselves and between the same and said plate.

14. The process for making treads and the like, which consists of enveloping the several elements in a mold, then passing the 30 filled mold through a lead-pot to introduce the lead into the mold, and then subsequently withdrawing and cooling the mold and contents.

15. The process for casting lead in tread- 35 plates, which consists in enveloping the tread-plate in a mold, then passing same through a lead-pot to cast, and subsequently cooling same.

16. The process of heated-mold-casting, 40 which consists in propelling a series of molds bodily into and through and out of a lead-pot.

17. The process of manufacturing anti-slip treads, which consists in temporarily 45 positioning carborundum or other abrasive material in proper relation to a foundation-plate within a suitable two-part mold to constitute a casting-unit, then subjecting said units to heat and pressure while simultaneously introducing molten lead or other binder into the interior thereof, whereby the carborundum is bound together and simultaneously bound to the foundation-plate.

18. The process of manufacturing anti- 55 slip treads, which consists in temporarily positioning carborundum or other abrasive material in proper relation to a foundation-plate within a suitable mold to constitute a casting-unit, then propelling said unit 60 through a heated casting-chamber containing molten lead or other binder, whereby the mold and its contents are heated and the molten binder introduced into the abrasive and the abrasive bound together and simultaneously bound to the foundation-plate.

19. The process of making treads composed of a hard metal base plate surmounted by a soft metal binder attached to the hard metal base plate and having contained within the soft metal binder hard particles, which 70 consists of introducing soft metal into the interstices between the particles themselves and of attaching the soft metal to the base plate.

20. In a tread manufacturing apparatus, 75 the combination of an open ended trough, a second trough located therein, and means such as a blank dummy or a casting unit for spacing the inner trough above the floor of the outer trough to constitute a casting 80 chamber and to close the outlet therefrom.

21. In a tread manufacturing apparatus, 85 the combination of a casting trough for molten lead or the like and a cooling region in front thereof with a continuous passage-way through the two, and means for feeding molds or casting units through said passage-way.

22. The combination with a tread manufacturing apparatus which comprises a casting chamber having a continuous passage-way therethrough, of a casting unit or the like adapted to pass through said passage and to close the outlet therefrom.

23. In a machine for making treads, a 95 casting machine comprising a lead pot having a trough-like portion adapted to act as a slide through which a mold may be slid, a movable cover for the slide and cooling devices at the lower end of the slide. 100

24. In a machine for making treads, a casting machine comprising a lead pot having a trough-like member adapted to act as a slide through which a mold may be slid and a cooling device at the lower end of the 105 slide.

25. The process of manufacturing anti-slip treads which consists in temporarily 110 positioning carborundum or other abrasive material in proper relation to a foundation plate within a suitable mold to constitute a casting unit, then subjecting the unit to heat and pressure while simultaneously introducing molten lead or other binder into the interior of the mold in the interstices of the 115 abrasive material whereby the carborundum is bound together and simultaneously bound to the foundation plate.

26. The process of making treads composed of a base of strong material surmounted by a wearing surface of soft material having grit embedded therein, which 120 consists of introducing soft material in the interstices of the grit and attaching the soft material to the strong material. 125

27. The process of making treads composed of a base of strong material coated with a surface of soft material and having granular material embedded therein, which 130 consists of coating strong material with soft

material and embedding granular material therein.

28. In a casting machine, the combination of a guide device provided with an entrance and an exit, a plurality of mold-sections in mating relation arranged to pass through the guide device and to hold a lengthy body of molten metal to be solidified into a casting, means for progressively moving the mold-sections and the contents thereof through the guide device, and cooling means adjacent the path of travel of the mold-sections for solidifying the contents of the mold-sections progressively in relation to the length thereof before emerging from the exit of the guide device.

29. In a casting machine, the combination of a guide device having a movable spring-maintained guide member and provided

with an entrance and an exit, a plurality of 20 mold-sections held in mating relation by the spring-maintained guide member and arranged to pass through the guide device and to hold a lengthy body of molten metal to be solidified into a casting, means for progressively moving the mold-sections and contents thereof through the guide device, and cooling means adjacent the path of travel of the mold-sections for solidifying the contents of the mold-sections progressively 25 in relation to the length thereof before emerging from the exit of the guide device. 30
